FIG. 1.

FIG. 2.

INVENTOR -
HARRY H. BECKWITH

BY Leighton & Sonnenburg, May
ATTORNEYS.

UNITED STATES PATENT OFFICE.

HARRY H. BECKWITH, OF BROOKLINE, MASSACHUSETTS.

SHOE-STIFFENER.

1,209,661.

Specification of Letters Patent. Patented Dec. 26, 1916.

Application filed July 28, 1915. Serial No. 42,330.

To all whom it may concern:

Be it known that I, HARRY H. BECKWITH, a citizen of the United States, and a resident of Brookline, in the county of Norfolk and State of Massachusetts, have invented 5 certain new and useful Improvements in Shoe-Stiffeners, of which the following is a specification.

This invention has relation to stiffeners 10 for boots and shoes, of the type in which, though relatively stiff and resilient, the blanks may be softened so that when assembled with the remainder of the upper, they may be molded to the shape of the last 15 end, and permitted to set or harden so as to form a box or counter for the toe or heel portion of the shoe.

According to the present invention, I employ as a base or foundation a body of 20 fibrous material such as wool felt, or its equivalent, which may be readily saturated or impregnated with the stiffening compound. This latter compound consists of some substance or combination of substances 25 which will soften at moderate heat, and which will quickly harden on cooling. I may employ Montan wax and refined asphalt, as pointed out in my Letters Patent No. 1,124,835, dated January 12, 1914, or I 30 may employ any other asphaltum or hydro-carbon blended with a resinous body and having a softening point which will permit the impregnated body to become soft and easily molded at low temperature—say from 35 150° to 200° F. After the sheet is impregnated with the stiffening compound and has cooled and hardened, it is cut into blanks of the desired shapes or sizes, and one or more edges thereof are skived, according to the 40 use to which the blank is to be put. This skiving tends to disintegrate the impregnating compound to some extent and to produce a fine dust therefrom which collects on the surfaces of the blank, and also tends to leave 45 the skived edges more or less rough. Then, for the purpose of compacting the blanks, resealing the fibers thereof and imparting an exterior finish, I subject the blanks to a further operation. That is to say, I subject 50 them to heat and pressure, and preferably apply a finishing coating of any suitable resinous substance. Any suitable pressing and heating apparatus may be employed for the purpose. I have found that desirable 55 results may be secured by passing the blanks between pressure rolls, of which one

is provided with a shoe or covering of more or less yielding material. One or both of these rolls may be heated. The resinous material may be supplied to either or both 60 of these rolls, so that, as the blanks are passed between them, it receives the further skin coating of said material. As a result of this treatment, the stiffening saturating compound, including the dust on the surfaces and raw edges, is more or less re-softened, the fibrous body is compacted, the surfaces are smoothed and more or less calendered, and the blanks are ready for shipment and use. 65

On the accompanying drawings,—Figure 1 shows a box toe blank embodying the invention. Fig. 2 shows conventionally pressure rolls such as may be employed in the final treatment of the blanks. 70

I have selected for illustration a box toe blank 3, having the skived edges 4, but the blank, if desired, may be formed for use as a counter. 75

After the blank has been preliminarily 80 formed as herein previously described, it may be passed between the pressure rolls which are conventionally shown in Fig. 2. The upper roll is shown as having a core 6 and a shoe or covering 5 of some suitable 85 cushioning or yielding material, such for example as felt, which during its use becomes more or less impregnated with the coating compound. This roll may be internally heated, if desired, but I find that 90 sufficient heat is imparted thereto from the roll 7. This latter roll is metallic and is chambered to permit the circulation of steam or hot water therethrough, so as to raise its temperature high enough to soften 95 or partially soften the blanks passing between the rolls. The rolls may be driven by any suitable means either at the same or at different peripheral speeds, and they are preferably adjusted toward each other 100 to impart the desired pressure to the faces of the blanks. By any suitable means, as by manual application from time to time, the coating compound of carnauba wax and paraffin wax, or of Montan wax, is applied 105 to the cushioned roll, and, by contact of the rolls, is spread evenly on the peripheries of both. Then, when the blanks are passed between the rolls, they are compacted and resealed, as it were, and are coated with a 110 thin layer of the resinous compound. Preferably, though not necessarily, the skived

faces or edges of the blanks are presented to the metallic roll, as the blanks are passed through the rolls, the cushion shoe of the upper roll yielding to permit the passage 5 of the thicker portion of the blank.

As a result of the process or method of treatment herein outlined, I provide as a new article of manufacture a blank of the character described, which is compacted by 10 pressure, and which, if desired, has an additional coating of resinous material, which is more or less absorbed by the fibrous body of the blank.

Having thus explained my new article of 15 manufacture, and a way of making the same, without attempting to describe all of the forms in which it may be made or all of the modes of its use, what I claim is:

1. As a new article of manufacture, a shoe 20 stiffener, consisting of a skived blank of fibrous material containing a stiffening compound adapted to be softened by moderate heat, said blank including its skived portion being compacted by pressure applied subsequently to the skiving of the blank.

2. As a new article of manufacture, a shoe 25 stiffener consisting of a skived-edge blank formed of fibrous material impregnated with a stiffening compound adapted to be softened by moderate heat, said blank having on its body and skived portions an additional coating of stiffening material adapted to be softened by heat.

3. As a new article of manufacture, a shoe

stiffener, consisting of a skived edge blank 35 of fibrous material containing a stiffening compound adapted to be softened by moderate heat, said blank including its skived edge being compacted and having a surface coating of stiffening material additional to 40 said stiffening compound adapted to be softened by heat.

4. The herein described process which consists in impregnating a fibrous body with a stiffening compound adapted to be softened by 45 moderate heat, cutting a shoe stiffener blank from said body, and then compacting such blank under conditions of heat and pressure.

5. The herein described process which 50 consists in skiving a shoe stiffener blank of fibrous material saturated with a stiffening compound adapted to be softened under moderate heat, and then subjecting the skived blank to heat and pressure to compact the same.

6. The herein described process which consists in skiving a shoe stiffener blank of fibrous material saturated with a stiffening compound adapted to be softened under 60 moderate heat, subjecting said blank to heat and pressure, and simultaneously applying a stiffening compound to the surface of said blank.

In testimony whereof I have affixed my 65 signature.

HARRY H. BECKWITH.
